ORGANIC BISMUTH COMPOUNDS OF HYDROAROMATIC ENDOMETHYLENE BENZOIC ACIDS

Max Bockmühl, Walter Persch, and Gustav Ehrhart, Frankfort-on-the-Main-Hochst, Germany, assignors to Winthrop Chemical Company, Inc., New York, N. Y., a corporation of New York

No Drawing. Application November 7, 1933, Serial No. 697,078. In Germany November 8, 1932

7 Claims. (Cl. 260—11)

The present invention relates to organic bismuth compounds of hydroaromatic endomethylene benzoic acids.

We have found that the bismuth salts of wholly or partially hydrogenated endo-methylene-benzoic acids possess good chemotherapeutic properties. Suitable acids of the said kind are the endo-methylene-benzoic acid obtainable by oxidation of camphene and similar compounds, for instance, 10 the camphenilanic acid of the formula

or the acid of the following formula

30 obtainable by oxidation of meta-pinene. With the same success there may be used endo-methylene-benzoic acids obtainable by diene-synthesis, for instance, from cyclopentadiene compounds and crotonic acid, e. g. the endo-methylene-tetrahydro-methylbenzoic acid of the formula

or the homologous acid of the formula

In the latter case the unsaturated endo-methylene-carboxylic acids obtained as well as the corresponding saturated endo-methylene-carboxylic acids may be transformed into their bismuth salts. The saturated endo-methylene-carboxylic acids 5 are obtainable from the unsaturated acids by hydrogenation. There may be used for instance, the endo-methylene-hexahydrobenzoic acid of the formula

or the endo-methylene-hexahydromethylbenzoic acid of the formula

or the endo-methylene-hexahydroethylbenzoic acid of the formula

There may also be used endo-methylene-benzoic acids, wherein the endo-methylene-hydrogen atoms have been exchanged for alkyl groups, for 40 instance, the camphane-carboxylic acids of the formula

Finally there may be used substitution products, for instance, of hydroxycamphenilanic acid of the formula:

15 The monoiodo-endomethylene-hexahydromethylbenzoic acid obtainable by addition of hydrogen iodide to the endo-methylene-2.5-delta₂-tetrahydro-6-methylbenzoic acid, the corresponding diiodo-endomethylene-hexahydromethylbenzoic acid obtainable by addition of iodine to the same parent acid, the mono-iodo-endomethylene-tetrahydromethylbenzoic acid obtainable by splitting off hydrogen iodide from the diiodo-endomethylene-hexahydromethylbenzoic acid, finally nitrated, partially or wholly hydrogenated endo-methylene-benzoic acids.

20 25 The salts of the formula (R)₃Bi and those of the formula R.Bi=O, wherein R stands for the radical of a wholly or partially hydrogenated endo-methylene-benzoic acid, are therapeutically valuable compounds.

30 35 They can be obtained by causing a bismuth salt to act upon a wholly or partially hydrogenated endo-methylene-benzoic acid. The new bismuth compounds are amorphous substances which decompose without melting when heated, and are insoluble in water, soluble in ether, chloroform and oils and have a strong bactericidal action especially against spirilli, but only a comparatively small toxicity.

30 40 The following examples illustrate the invention: (1) 51 grams of camphenilanic acid (cf. Beilstein, 4th edition, volume 9, page 74) are dissolved together with 12 grams of caustic soda in 150 cc. of water. The solution is mixed with a solution of 48.5 grams of crystallized bismuth nitrate in 150 cc. of glycerine and 300 cc. of water. The white precipitate obtained is washed with water and dried. It is the bismuth salt of the camphenilanic acid, readily soluble in chloroform, benzene, ether and oils, insoluble in water and containing 29.7 per cent. of bismuth (calculated 29.4 per cent. for (C₁₀H₁₅O₂)₃Bi).

45 50 (2) 3.5 grams of isocamphenilanic acid (Beilstein, 4th edition, volume 9, page 74) are dissolved in 50 cc. of water together with 22 cc. of N-caustic soda solution. The solution is mixed with a solution of 3.5 grams of crystallized bismuth nitrate in 10 cc. of glycerine and 20 cc. of water. The product is worked up as indicated in Example 1. The colorless bismuth compound has the same physical properties as the bismuth salt of camphenilanic acid.

55 60 (3) There are dissolved in 15 cc. of alcohol 15.2 grams of endo-methylene-2.5-delta₂-tetrahydro-6-methylbenzoic acid (obtained from cyclopentadiene and crotonic acid by the method described in "Annalen", volume 460, page 117): colorless apparently rhombic tablets melting at 96° C. to 97° C.). The solution is neutralized with caustic soda solution and the bismuth salt is precipitated, while stirring and cooling, by adding a solution of 16.2 grams of bismuth nitrate in 46 grams of an aqueous mannite solution of 13 per cent. strength. The resultant white voluminous precipitate is soluble in ether, benzene and olive oil 70 and contains 31.6 per cent. of bismuth; it, there-

fore, corresponds with the formula: (C₉H₁₁O₂)₃Bi.

5 10 (4) 18 grams of camphenane-carboxylic acid are dissolved in 100 cc. of N-caustic soda solution. The solution obtained is mixed with a solution of 17 grams of bismuth nitrate, 8 grams of mannite and 100 cc. of water. The bismuth salt of camphenane-carboxylic acid which is thus precipitated is filtered by suction and washed with water. It is readily soluble in ether, chloroform and oils, sparingly soluble in water.

10 15 (5) 16.8 grams of camphenilanic acid are dissolved together with 4 grams of caustic soda in 150 cc. of water. Into the solution so obtained there are simultaneously introduced, while stirring, a solution of 48.5 grams of crystallized bismuth nitrate in 150 cc. of glycerine and 300 cc. of water and a solution of 8 grams of caustic soda in 100 cc. of water in such a manner that the liquid always shows an alkaline reaction to litmus paper. The white precipitate obtained is filtered by suction, washed with water and then dissolved in benzene. By evaporating the dried filtered benzene solution there is obtained the bismuth-oxide salt of camphenilanic acid of the formula C₁₀H₁₅O₂.BiO soluble in oil. The product contains 25 33.3 per cent. of bismuth (theory 53.3 per cent.).

20 25 We claim:

1. The bismuth salts of acids of the following formula R.COONa in which R stands for a hydroaromatic hydrocarbon radical of the endo-methylene-benzene series, said salts being amorphous substances, insoluble in water, soluble in ether, chloroform and oils, decomposing without melting when heated and having a strong bactericidal action, especially against spirilli.

30 35 2. The bismuth salts of acids of the following formula R.COONa in which R stands for a wholly hydrogenated hydrocarbon radical of the endomethylene-benzene series, said salts being amorphous substances, insoluble in water, soluble in ether, chloroform and oils, decomposing without melting when heated and having a strong bactericidal action, especially against spirilli.

40 45 3. The bismuth salts of acids of the following formula

55 60 in which R stands for the radical of a wholly hydrogenated hydrocarbon of the endomethylene-benzene series substituted by lower alkyl groups, said salts being amorphous substances, insoluble in water, soluble in ether, chloroform and oils, decomposing without melting when heated and having a strong bactericidal action, especially against spirilli.

65 70 4. The bismuth salts of the acids of the following formula

70 75 in which R stands for the radical of a wholly hydrogenated hydrocarbon of the endomethylene-benzene series substituted by methyl groups, said compounds being amorphous substances, insoluble in water, soluble in ether, chloroform and oils, decomposing without melting when heated and having a strong bactericidal action, especially against spirilli.

5. The bismuth salt of camphenilanic acid of
the following formula:

15 said salt being an amorphous substance, insoluble in water, soluble in ether, chloroform and oils, decomposing without melting when heated and having a strong bactericidal action, especially against spirilli.

20 6. The bismuth salt of isocamphenilanic acid, said salt being an amorphous substance, insoluble in water, soluble in ether, chloroform and oils, decomposing without melting when heated and having a strong bactericidal action, especially against spirilli.

7. The bismuth salt of camphane-carboxylic acid of the following formula:

10 15 said salt being an amorphous substance, insoluble in water, soluble in ether, chloroform and oils, decomposing without melting when heated and having a strong bactericidal action, especially against spirilli.
